UNITED STATES PATENT OFFICE.

HARRY R. COFFEY, OF CHICAGO, ILLINOIS.

ELECTRIC-LIGHT SWITCH.

No. 857,384.

Specification of Letters Patent.

Patented June 18, 1907.

Application filed January 7, 1907. Serial No. 351,156.

To all whom it may concern:

Be it known that I, HARRY R. COFFEY, a citizen of the United States, residing at Chicago, in the county of Cook and State of Illinois, have invented certain new and useful Improvements in Electric-Light Switches, of which the following is a specification.

The object of my invention is to provide means for obviating the difficulty in turning the switches of overhead lights, which are frequently placed so high as to be out of reach.

With this object in view I have devised means whereby chains, cords or other pendent members can be attached to the usual handle of an electric light switch. The pendent members are of such length as to hang within easy reach and the switch can be closed or opened by pulling upon one or the other of said members.

In the drawing—Figure 1 is a view of an incandescent lamp with my invention applied thereto; Fig. 2 is a perspective view of the attachment separated from the lamp; 25 and Fig. 3 is a fragmentary view of a part of the attachment.

I have shown my invention in connection with an incandescent lamp socket of common construction. In those cases where the 30 socket is turned so that the handle *a* of the switch is on the lower side, it will be found advantageous to turn the socket to the position shown in Fig. 1 of the drawing, in which figure the handle is shown projecting 35 at the side of the socket. The form of socket generally in use may be turned by simply loosening the usual set screw which holds it in place.

The form of my invention shown in the 40 drawing comprises a strip of metal *n*, preferably of brass, bent to the form shown in Fig. 2. In this figure I have shown the metal strip bent to conform to the shape of the usual handle *a* of the light switch and 45 formed with outwardly extending lips *o*, *o'*. The lips *o*, *o'* are provided with apertures for the reception of a screw threaded lever member *p*. The aperture in the lip *o'* is screw threaded. In punching the hole in the lip *o'* 50 sufficient metal will be outwardly deflected

as shown at *q* to afford space for several screw threads, even when the metal operated upon is comparatively thin. The screw *p* is formed with a shoulder *r* designed to abut against the ear *o*, the aperture in which is not 55 provided with a screw thread.

It will be obvious that this construction affords means for securely drawing the clamping member *n* in place upon the switch handle *a* by tightening the screw *p*. The 60 interior of the clamping member *n* is preferably roughened in some manner in order to insure a more secure hold upon the switch handle *a*. In the present instance I have shown inwardly deflected points *m* formed 65 by slitting and striking inwardly a portion of the metal of which the clamping member is formed. It will be obvious, however, that other means might be adopted for the same purpose. Chains or other pendent 70 members are attached to the ends of the screw *p*, which is made of sufficient length to afford the necessary leverage for turning the switch when tension is applied to such pendent members. In the present instance 75 I have shown apertures in the ends of the screw and rings inserted therein to which the pendent members are attached. While I have shown these pendent members in the form of chains, it will be obvious that cords 80 or ribbons might be substituted therefor. At the lower ends of the chains I have shown rings *k*, *l* to afford a more efficient hold for the hand.

It will be obvious that the switch may be 85 moved from the closed to the open position, or vice versa, by pulling upon the proper chain.

While I have described one specific form of my invention, my invention is not limited 90 to that specific form, but covers the features set forth in the following claims.

What I claim is—

1. An attachment for electric switches, comprising a clamping member formed to fit the switch handle, said clamping member having outwardly extending lips, a lever member mounted in said lips, said lever member having means co-operating with the lips for adjusting the clamping members on 100

the handle, and operating members attached to the ends of the lever member.

2. An attachment for electric switches, comprising a clamping member formed to fit the switch handle, apertures in the ends of said clamping member, one of said apertures being screw threaded, a shouldered

screw passing through said apertures, and pendent members attached to the ends of said screw.

H. R. COFFEY.
